VIBRATING SCREEN

William A. Fye, Hollidaysburg, Pa., assignor to
McLanahan & Stone Corporation, Hollidays-
burg, Pa., a corporation of Pennsylvania

Application May 24, 1937, Serial No. 144,496

2 Claims. (Cl. 209—415)

This invention relates in general to screens of the vibratory type, and more particularly to improved means for mounting or fastening the screen box to its stationary frame.

5 The invention consists in the provision of improved spring means for fastening or supporting the screen box on its supporting frame so that the screen box is not carried by compression, as is now the case when using resilient means such 10 as springs for this purpose, but rather, so that the screen box is carried by torsion on the spring.

A further object of the invention is to provide improved means for adjusting the torsion on the springs supporting or fastening the screen box 15 to its supporting frame.

The invention, together with its objects and advantages will be best understood from the following description taken in connection with the accompanying drawings, wherein:

20 Figure 1 is a top plan view of a vibratory screen having my invention applied thereto.

Figure 2 is a longitudinal sectional view through the screen.

25 Figure 3 is a fragmentary detail sectional view showing the improved spring support or fastening means for the screen box.

Figure 4 is a detail elevational view showing one of my improved spring supports for the screen box.

30 Figure 5 is a fragmentary detail sectional view showing the manner of securing the upper and lower screen cloths within the screen box.

Referring to the drawings by reference numerals, it will be seen that I have illustrated the 35 invention as applied to a vibratory screen which includes, among other parts, the screen box 5 and supporting frame or beams 6—6. The upper and lower screen cloths are indicated by the reference numerals 7 and 8 respectively, and as 40 shown in Figure 5 at the longitudinal edges thereof the screen cloths are provided with angle iron frame members 9 which rest on angle iron ledges 10 provided on the sides of the screen box and cooperable with channel bars 11 for securing 45 the screens in place, channel bars 11 being secured to the sides of the box 5 through the medium of bolts 12 as shown.

In accordance with the present invention there are provided four spring assemblies 13 for supporting the screen box 5 from the stationary beams 6 and these spring assemblies 13 are arranged as shown in Figure 1, wherein it will be seen that the spring assemblies 13 are arranged at opposite sides of the box 5 and adjacent the 55 respective opposite ends of the box.

As clearly shown in Figures 3 and 4, each spring assembly 13 includes a bearing member 14 bolted or otherwise secured as at 15 to the supporting beam 6. A bolt 16 has a diametrically enlarged intermediate portion fitting within the bearing 14 as shown in Figure 3 and a reduced longitudinally split end portion 17, together with a non-circular or hexagonal end 18.

5 A coil spring 19 has one end thereof disposed within the slot 20 provided in the bolt end 17, and said bolt end at its terminal is provided with threads to receive a nut 21 that serves to contract the end 17 of the bolt to clamp the said end of the spring 19 securely within the slot 20 in said bolt end 17.

10 At the free end thereof the spring 19 is provided with an eye 22 that is secured to a bolt 23 projecting from one side of the screen box 5 as will be clear from a study of Figures 1 and 4.

To secure the bolt 16 against turning movement within the bearing 14, and the spring 19 with its tension at the desired adjustment, there is sleeved onto the hexagonal end 18 of the bolt a ferrule 24 that has a conformable fit on the end 18 of the bolt 16 and is provided externally 25 with an annular series of ribs or teeth 25 that engage complementary internal teeth 26 provided in the bearing 14 at one end of the bore of said bearing as shown in Figure 3.

20 A cotter pin or the like 27 may be resorted to for securing the ferrule 24 against accidental sliding movement along the end 18 of bolt 16.

25 It will thus be seen that I have provided a resilient or spring support for the screen box 5 whereby the latter is supported in a resilient 30 manner from the stationary beam 6 of the screen assembly.

When it is desired to tighten a spring 19 the ferrule 24 is slid outwardly to disengage the teeth 25 thereof from the teeth 26 and by applying a 40 wrench or the like to the end 18 of the bolt the latter is given a sufficient number of turns so as to wind the spring thereon an amount sufficient to carry the weight of the screen box. When this has been completed, the ferrule 24 is 45 slid into the position as shown in Figure 3 with the teeth 25 thereof meshing with the teeth 26 of the bearing 14 whereby the bolt 16 is held against rotative movement.

50 A spring supporting arrangement as comprehended by the present invention finds its merits in that the screen box is not carried by compression on the springs but rather by torsion, and the arrangement of bearing, ferrule, and bolt, provides for each of the springs a method 55

of adjusting this tension so that the screen box is carried in correct position at all times and under all circumstances.

It is thought that a clear understanding of the 5 construction, utility and advantages of an invention of this character will be had without a more detailed description.

Having thus described the invention, what is claimed as new is:

- 10 1. Supporting means for resiliently supporting a vibratory screen box from a stationary supporting means, and including a bearing mounted on the supporting means, a bolt having an intermediate cylindrical portion journalled in 15 said bearing, said bolt having a longitudinally split end and a hexagonal end respectively, said split end being provided with threads, a coil spring disposed substantially concentric to the split end of the bolt and having an end engaged 20 in the slit of said bolt end, a nut threaded on the threaded end of the bolt for securing said end of the spring engaged with the bolt, means securing the free end of the screen to one side of

the screen box, a ferrule sleeved on and conformably fitting the hexagonal end of said bolt and provided with an external circumferential series of teeth, and said bearing having a circular series of internal teeth complementary to the teeth 5 on said ferrule for securing the bolt against rotative movement.

2. In a vibratory screen structure, a screen box, supporting means for the screen box, a bearing mounted on said supporting means, a bolt having 10 a portion thereof journalled in said bearing, a coil spring disposed about one end of the bolt laterally of said bearing and having an end secured to the bolt, said coil spring also having a second end secured to the screen box at one side of 15 the latter, and said bolt being rotatable in the bearing for adjusting the tension of said spring, a ferrule on the bolt to rotate therewith, and inter-engaging means on said bearing and said ferrule for securing the bolt at the desired position of rotative adjustment. 20

WILLIAM A. FYE.
